CLAIM

The ornamental design for a plumbing fitting, as shown and described.

DESCRIPTION

FIG. 1 is a top, left, front perspective view of a plumbing fitting showing another embodiment of our new design; FIG. 2 is a left side elevational view thereof; FIG. 3 is a right side elevational view thereof; FIG. 4 is a front elevational view thereof; FIG. 5 is a rear elevational view thereof; FIG. 6 is a top plan view thereof; and, FIG. 7 is a bottom plan view thereof.

The broken line representations in the figures show unclaimed environment, and thus form no part of the claimed design.

The nature of this product is a plumbing fitting, such as a spout for a sensor activated faucet.
